Primary Examiner — Cynthia Ramirez*Assistant Examiner* — Tamara L Hahn(74) *Attorney, Agent, or Firm* — William H. Dippert;
Laurence A. Greenberg; Werner H. Stemmer(57) **CLAIM**

The ornamental design for an open top trash can, as shown and described.

DESCRIPTION

FIG. 1 is a perspective view of an open top trash can, showing my new design.

FIG. 2 is a top plan view thereof.

FIG. 3 is a front elevation view thereof.

FIG. 4 is a left-side elevation view thereof.

FIG. 5 is a rear elevation view thereof.

FIG. 6 is a bottom plan view thereof; and,

FIG. 7 is a right-side elevation view thereof.

The broken lines in the drawings represent portions of the open top trash can that form no part of the claimed design.
